UNITED STATES PATENT OFFICE.

HAROLD C. SUEKERT, OF NEW YORK, N. Y., ASSIGNOR TO AUTOMOTIVE SUPPLY COMPANY, INC., OF NEW YORK, N. Y., A CORPORATION OF NEW YORK.

FUEL-FEEDING APPARATUS AND CONTROL THEREFOR.

Application filed June 17, 1920. Serial No. 389,722.

To all whom it may concern:

Be it known that I, HAROLD C. SUEKERT, a citizen of the United States, and a resident of the city, county, and State of New York, have invented certain new and useful Improvements in Fuel-Feeding Apparatus and Control Therefor, of which the following is a specification.

My invention relates to apparatus for feeding fuel as from the fuel tank of an automotive vehicle or device to the carbureting apparatus of an internal combustion motor located above the level of the fuel tank, and two means for controlling the same.

According to the present invention, a fuel pump is operated from a source of pulsating pressure, preferably a cylinder of an internal combustion motor, and the same 20 is directly controlled by the fuel pumped so that the pump is held from operation after sufficient fuel has been supplied by the pump and when the fuel has been used up to a sufficient extent to require further 25 pumping, the pump is automatically released and the pumping action resumed.

This can be accomplished in a variety of ways within the scope of my invention, but in the illustrative form shown for the purpose of making my invention clearly understood—though not for purposes of limitation of the invention—I have shown the pump passing through a clutch member which normally permits the pump rod to reciprocate freely but which, when moved to clutching position, operates to hold the pump against movement and I have shown the fuel being pumped into a closed or pressure tank and the clutch member operated 40 from a diaphragm, which is actuated in one direction from the pressure in the tank and the opposite direction by means of a spring.

In the drawings, showing the said embodiment of my invention, Fig. 1 is a vertical sectional view of the apparatus. Fig. 2 is a horizontal section on the line 2—2, Fig. 1. Fig. 3 is a detail sectional view on the line 3—3, Fig. 1. Fig. 4 is a fragmental sectional detail view, showing the clutch 50 member in holding position.

Reference character 10 designates the fuel reservoir adapted to contain liquid fuel, such as gasoline, under pressure.

The reservoir 10 has a ring 11 soldered 55 or otherwise secured thereto about its up-

ward margin and to which a casting 12 is removably secured, as by means of screws 13.

Casting 12 has a downwardly extending portion or boss 14 and a recess 15 is formed in the upper face of casting 12. A shell 16 is secured to the lower side of the casting 12 and contains a diaphragm 17. A stem 18 is secured to the diaphragm 17 and is provided with a head 19 extending into a recess 15 for operating the clutch member 20.

On top of the casting 12 is secured a plate 21, which covers the recess 15 and is provided with an upward extension 22 containing an adjustably held spring 23 which 70 actuates slide 24 to normally hold the clutch member in inoperative position, as shown in Fig. 1. Cylinder 25 is secured on plate 21 in line with boss 14 and is preferably provided with cooling fins 25.

Cylinder 25 receives the piston 26 and is in communication as through a port 27 in its upper end with a source of pulsating pressure which may be provided by connecting same with a cylinder of an internal combustion engine. The connection between the cylinder 25 and the engine cylinder is open at all times.

The pump rod 28 is secured to the piston 26 and is encircled by a spring 29, tending to raise piston 26. A bumper 30 of cork, or equivalent material, is provided in order to cushion excessive shocks due to violent downward movement of piston 26. The space beneath piston 26 is in free communication with the outside air as by means of port 31. The pump rod 28 passes through an opening 21' in the clutch member 20 and through the bore 14' of the boss 14 on casting 12 and is provided in such bore 14' with a suitable packing or gland which may consist of cotton, or other packing material 32 interposed between washers 33, 33 of cork, or the like material.

A pump cup 34 is secured to the lower end of the pump rod 28 and contains a bumper 35 to cushion upward movement of the reciprocable pumping device, including piston 26, pump rod 28 and cup 34.

The fuel inlet is at 36 and the incoming fuel passes downwardly through passage 37 on the down stroke of the pump. The boss 14 has a flexible washer 38 secured thereto and adapted to close against the cup 34 to prevent fuel passing backwardly from the 110

reservoir 10 to the pump on the down stroke of the latter, and also adapted to give a free outlet of relatively large cross section from the pump to the reservoir on the up stroke of the pump. If desired, passages 36, 37 may be provided with a check valve to prevent backward movement of the fuel through these passages but this is not essential since with the device constructed as shown, while 10 more or less fuel will move backwardly in passage 37 on the up stroke of the pump a sufficient proportion thereof will pass into the reservoir 10 about the flexible washer 38 to supply requirements for engine fuel.

15 A siphon outlet for the fuel is provided in reservoir 10 of the type described and claimed on my prior copending application, Ser. No. 335,648, filed November 4, 1919, and may comprise an outer tube 39 having the plug 40 in its upper end and having inlet openings 41 at or near its lower end and containing an interior fuel outlet tube 42 having the openings 43 at or near the upper end thereof and forming a siphon 20 passage comprising the annular opening 44 and the bore 45 of tube 42. Plug 40 is provided with a downwardly extending tubular portion 46 having a bore 47 extending through the upper face of plug 40 and the 25 said tubular extension 46 having the lower end thereof located a substantial distance below the inlets 41 of the siphon so as not to break the siphon seal. Passage 47 provides an outlet for air for gases and prevents an excessive accumulation thereof 30 within the reservoir 10; such excess gases passing out with the fuel to the carburetor.

35 The mode of controlling the fuel feeding apparatus will be readily understood in connection with the foregoing.

40 The reciprocable pumping apparatus normally moves up and down in response to pulsations of pressure in the engine cylinder which are communicated thereto at all time while the engine is in operation 45 and the fuel is pumped into the reservoir entering passage 37 on the downstroke of the pump and being discharged past the flexible washer 38 on the up stroke.

45 As the pressure rises in the reservoir 10 diaphragm 17 is forced upwardly by the pressure and the head 19 of the diaphragm stem 18 serves to turn the clutch member 20 on its pivot screws 48, 48 (Fig. 2) against 50 the action of spring 23 into the position shown on Fig. 4 in which the pump rod 28 is held against movement by the canting action of clutch member 20 as will be readily understood, and thus the movement of the 55 reciprocable pumping device is stopped or reduced and is again resumed or increased as the fuel level, and therefore, the pressure in the reservoir falls upon outflow of the fuel to the carburetor or other device fed 60 from the reservoir 10.

65 The invention may be embodied in forms other than that shown herewith for the purpose of illustration, so long as same comes within the scope of my claim and makes use of the principle of the invention.

70 I claim:

75 1. In fuel feeding apparatus, fuel pumping means operated from the course of pulsating pressure and a clutch member controlled by the fuel pumped and adapted to clutch and hold the pumping means.

80 2. In fuel feeding apparatus, reciprocable fuel pumping means operated from a source of pulsating pressure, a clutch controlled by the fuel pumped and adapted to clutch and hold the pumping means against reciprocatory movement.

85 3. In fuel feeding apparatus, reciprocable fuel pumping means adapted to be permanently connected to an operating source of pulsating pressure such as a cylinder of an internal combustion engine, a pressure reservoir to which liquid fuel is pumped by said pumping means, a clutch for holding said pumping means stationary or substantially so, and means operated by the pressure in the reservoir for actuating said holding means when the pressure within the reservoir rises and for releasing same as the 90 pressure in the reservoir falls.

95 4. In fuel feeding apparatus, a reciprocable pumping device adapted to communicate with and be actuated by a source of pulsating pressure and comprising a reciprocable pump cup and a flexible washer within 100 said pump cup and a pump rod, a clutch adapted to cooperate with and hold said pump rod and means operated by the fuel pumped for controlling said clutch.

105 5. In fuel feeding apparatus, a reciprocable pumping device including a piston exposed to a source of pulsating pressure, a pump cup, a rod for connecting said piston and pump cup and a spring applied to 110 said rod, a tank to which fuel is pumped under pressure, and a clutch member adapted to cooperate with said pump and to clutch and hold the same, and means for actuating said clutch member adapted to be operated by change of pressure within the fuel reservoir.

115 6. In fuel feeding apparatus, reciprocable fuel pumping means including a pump rod, a pivoted clutch member having an opening through which said pump rod passes, and means controlled by the fuel pumped for actuating said clutch member to cant the same and thereby clutch and hold the pump rod against reciprocatory movement.

120 7. In a fuel feeding apparatus, a pumping means including a rod, a boss, a cup enclosing the boss and operated by the rod, a loose packing between the boss and cup to alternately inspire and expel the fuel into and 125 from the cup upon movement of the latter,

and means controlled by the accumulation of the fuel pumped to arrest or release operation of said pumping means.

8. In a fuel feeding apparatus, a pumping means including a reciprocable rod, a clutch means including an arm having an opening through which the rod passes, means to pivot said arm at points opposite the axis of the rod, and means operable by changes in pressure due to fuel accumulated to engage the free extremity of said arm whereby to rock the same and cause diagonally opposed edges at opposite sides of said arm to grip said rod to arrest reciprocation of the same.
9. In a fuel feeding device, a reservoir, a closure plate therefor, a boss formed on the plate extending into the reservoir, said boss having an inlet passage, a rod extending through said boss, a cup mounted on one end of said rod and enclosing the boss, a loose packing between the cup and boss, a chamber

25

ber mounted on the plate receiving the other end of the rod and designed for a communication with an engine cylinder, a piston carried by the rod fitting said chamber, whereby fuel may be fed to the reservoir by reciprocation of said cup, and means operable by pressure changes in the reservoir to control reciprocation of said rod.

10. A fuel feeding device including a reservoir, means to pump fuel therein, a bell shaped casing mounted in the reservoir, a diaphragm mounted in the large end of the casing, a rod anchored at one end to the diaphragm, and a clutch engageable by the other end of said rod to control operation of the pumping means upon changes of pressure in the reservoir.

30

35

In testimony that I claim the foregoing, I hereto set my hand, this 12 day of June, 1920.

HAROLD C. SUEKERT.
